PORTABLE FOLDING BOOM

Norman F. Hurst, Aurora, Oreg., assignor to
Ralph M. Osvold and Norman F. Hurst, a co-
partnership, doing business as Hurst Truck
Utilities, Portland, Oreg.

Application August 28, 1953, Serial No. 377,101

5 Claims. (Cl. 212—8)

1

This invention relates to booms for lifting loads and, more particularly, to portable booms of a type which may be collapsed and stowed on a truck body when not in use.

There have been many prior art suggestions for the construction of portable booms. One type with which I am familiar has two side legs which are raised and lowered by hydraulic cylinders. Another type has two side legs and a hydraulically operated middle or brace leg which positions the two side legs. In stowed position the legs of either type of boom are folded or telescoped. When the boom has been raised and prior to being put in operative use, the upper portions of the legs must usually be securely fastened to the lower portions by some locking means such as pins or latches. Such arrangements are cumbersome and necessitate an extra manual operation on the part of someone, which is dangerous in that the boom may collapse if it has not been securely fastened, or if one is working around overhead high tension wires, a person setting a latch is in danger of being electrocuted. There are also certain confining limitations on the type of work and locations in which the booms heretofore known can successfully operate. Additionally, with three-legged booms the middle leg, of necessity, is positioned in the center of the truck body where it takes up space which could well be utilized for the stowage of materials or tools.

While my invention is generally applicable to all vehicles, it has been found to be particularly suited for public utility service trucks of the type used for setting and removing poles carrying overhead lines, transformers, and other equipment.

According to my invention, the folding boom comprises a pair of legs which are joined at their apex and in carrying position normally lie flat on the top of the truck with their apex over the cab of the truck. At their free ends, the legs are pivotally mounted in vertically slotted guideways at the rear of the truck. Connected to each leg near the apex is a piston from an hydraulic cylinder which is pivotally connected to the body of the truck and is free to follow the movement of the legs. There are mounted on the truck near the slotted guideways a pair of vertical cylinders whose pistons are connected to the pivoted ends of the legs. The first-mentioned pair of hydraulic cylinders control for the most part the erection and lowering of the legs as they are moved in an arc from an at rest position to operative positions at different angles to the body of the truck. The second pair of cylinders provide cushioned supports for the legs in the opera-

2

tive positions, and can also be utilized to vary the length of the legs.

It will be appreciated that some of the advantages and features afforded by my improved boom are simplification of construction; a "live" boom from the time it is first put into operation. By "live" is meant a boom whose position and length can be independently controlled while carrying a load. The inside body area of the truck is free for a stowage of tools and materials. If it is desired to drop a load directly into the truck, there is no boom operating gear which will interfere. Loads can be carried by the boom on either side of its vertical position which permits the boom being used to load and unload the truck itself. One man can operate the boom conveniently because it is unnecessary to fasten and unfasten folding leg members when they are put into and out of operative position. The cushioning action of the vertical hydraulic cylinders insures better and safer operation of the boom and may be operated simultaneously or independently of the other pair of cylinders to vary the length of the boom and provide an added area in which the boom has working positions. The combination of the two sets of cylinders generally gives much greater flexibility in the use of the boom and permits it to be adapted to varying conditions and eliminates to a great extent the necessity of having to move the truck for minor position adjustments of the boom.

On all other booms with which I am familiar, it is not possible to vary the height of the boom without moving it through an arc, and the only way in which the vertical position of the load being carried by the boom may be varied is by means of operating the winch to move the hook carrying the load. Frequently, it is desirable to be able to change the height at which a load is being carried without moving the boom in an arc or dropping the load and picking it up at another point. For example, when setting a telephone pole in a hole in the ground, it often happens that after the boom has been lifted to its position of maximum elevation, the pole does not clear the ground, permitting it to be set in the hole. With pre-existing booms, it is necessary to lower the pole to the ground and set the hook at a lower position on the pole. With my improved boom, this would not be necessary because after the boom had reached an upright position, the vertical cylinders can be operated to raise the boom and pole an extra amount sufficient, in the usual situation, to provide the necessary clearance so that the pole can be set in the hole. The ability

to raise the boom vertically is also very useful in situations where one is working with a boom in a relatively confined space, as between overhead wires. In this situation, the fact that the height of the boom can be varied in a vertical plane which includes the hook and apex of the boom is of great advantage over an arrangement where the boom can only be moved in an arc which, of course, presents a continual danger of fouling the overhead wires.

The advantages and features of the invention will become more apparent from the following detailed description taken in conjunction with the drawings, in which:

Fig. 1 is a side elevation of a truck with the improved boom thereon;

Fig. 2 is a rear end view of the truck and boom;

Fig. 3 is an enlarged section on lines 3—3 of Fig. 2;

Fig. 4 is an enlarged section on lines 4—4 of Fig. 2; and

Fig. 5 is a side elevation of a truck with the boom in two of its operative positions.

Referring to the drawings, the chassis of truck 10 has a body generally indicated at 11, having two sides 12 and 13. In between sides 12 and 13, there is a vacant space 14 which may be conveniently used for the storage of tools or other material which it is desired to carry on the truck. The top of the truck between sides 12 and 13 may be open, closed, or, as is more common, sliding, so that it may be converted from open to closed. The boom comprises two rigid upwardly converging legs 15, 16 which are joined to one another at an apex where there is provided a sheave 17. A cable 18 having a hook 19 at one end runs through sheave 17 and, by means of a suitable winch 20 on the truck, the cable may be operated to lift and lower loads fastened to the hook.

A pair of horizontal hydraulic cylinders 21, 22 are pivotally fastened at 23, 24 to supporting members 12' projecting slightly above the tops of the sides of the truck. Pistons 25, 26 in cylinders 21, 22 have their free ends fastened by brackets 27, 28 to each of legs 15, 16 at points nearer the apex of the legs than their rear ends. The rear ends of legs 15, 16 are flattened (Fig. 3) and welded to round bars 29, 30. Round bars 29, 30 extend into vertical slotted guideways 31, 32 which are formed between upstanding I-beams 33 and box beams 34. Washers 35, 36 surrounding bar 30 are provided on either side of the beams. Loosely fitting collars 37 surround the other ends of bars 29, 30 and are held thereon by means of washers 38 and nuts 39.

Collars 37 are fastened to the free ends of pistons 45, 46 which operate in vertical hydraulic cylinders 47, 48. Cylinders 47, 48 are mounted at the rear of the truck on either side and are in cooperative relation with slotted guideways 31, 32.

When the boom is in its at rest, or stowed, position, as shown in solid lines Figs. 1 and 2, cylinders 21, 22 are supported above the cab of the truck by supports 49. It should be noted that in this position the legs 15, 16 do not project from the rear of the truck as they so often do on other portable boom trucks.

Pipes 50, 51 conduct oil to the hydraulic cylinders. The construction of the cylinders or the manner in which they are operated is not shown as it forms no part of the present invention. Suitable standard hydraulic cylinders are available and they may be controlled in any one of a

number of ways familiar to those skilled in the art.

As best seen from Figs. 1 and 5, one of the features of the boom is that the combination of the vertical cylinders whose pistons are pivotally connected to the heels or bases of legs 15, 16 and the other pair of cylinders which move the legs through an arc permit the boom to be moved into any number of different vertical and horizontal positions within area X. In this manner, by means simply of moving the boom itself rather than the truck or hook, the boom while carrying a load can adapt itself to any number of situations. In this sense, the boom is truly a live boom throughout its range of operative positions.

Fig. 5 shows the boom in its two positions of maximum elevation. In the position shown in solid lines, the pistons 45, 46 are fully extended and pistons 25, 26 partially extended. In the position shown in dotted lines, the boom has been vertically lowered by completely retracting pistons 45, 46 and retracting pistons 25, 26 a little from the position shown in solid lines.

The boom is operated in the following manner: Commencing with the boom in stowed, or at rest, position on top of the truck, cylinders 21, 22 are operated and as their pistons 25, 26 are extended, legs 15, 16 are moved upwardly, in the direction indicated by the arrows in Fig. 1, in an arc as bars 29, 30 pivot in the guideways. If it is desired to move the boom into its position of maximum effective reach, pistons 25, 26 will be completely extended to move the boom substantially through 180° into horizontal position shown in dotted lines Fig. 1, and vertical pistons 45, 46 will be completely retracted into cylinders 47, 48 to provide sufficient triangulation so that a load may be hoisted. In this position the boom can be moved into otherwise inaccessible positions, such as under low hanging impediments, trees, buildings, etc. By retracting pistons 25, 26, the load which has been secured to hook 19 may be lifted and ultimately swung into space 14 in the truck, if desired.

As shown by area X, the boom has a wide range of operative positions into which it can be moved. The controls for the hydraulic cylinders may be conveniently located in the cab of the truck so that control of the boom can be a one man operation from the raising of the boom into operative position to stowing it back on top of the truck.

While a preferred embodiment of the invention has been here disclosed, it is to be understood that variations and changes in the apparatus will be suggested to those skilled in the art, and it is intended to encompass such variations and changes in the present invention which is to be limited only as defined in the appended claims.

I claim:

1. A portable folding boom for a vehicle or the like which is adapted to be moved into and out of operative position by one man comprising, a vehicle chassis, a supporting frame on the chassis, a pair of legs connected to one another at one end and separated from each other at the other end, a first pair of hydraulic cylinders pivotally supported at one end on said supporting frame, a piston extending from each of said cylinders and fastened to a corresponding leg, vertical guideways for slidably supporting said separated ends of the legs, bar means extending from each of said ends of the legs into the guideways, a second pair of hydraulic cylinders vertically

mounted in cooperative relation with said guideways, and a piston extending from each of said last-mentioned cylinders connected to said bar means.

2. A portable folding boom for a vehicle having a body with sides and a top, said boom having a normal at rest horizontal position in which it lies substantially flat on top of the vehicle body and operative positions in which it is raised at different angles to the body comprising a supporting frame, a pair of upwardly converging legs joined together at one end in an apex, a first pair of hydraulic cylinders having one end pivotally mounted on the frame and at the other end connected to each of the legs near the apex, 15 said first pair of cylinders being substantially horizontal in the at rest position of the legs, vertical guide means on either side of the vehicle body, the other end of said legs mounted in said guides, a second pair of vertically mounted hydraulic cylinders cooperating with the guides and connected at one end to the legs, and means for controlling the operation of said hydraulic cylinders.

3. A portable folding boom for a truck having a body with closed sides and sliding top, said boom having a normal at rest horizontal position in which it lies substantially flat on the top of the truck body and operative positions in which it is raised at different angles to the body, comprising a supporting frame, a pair of upwardly converging legs joined together at an apex and having free ends separated from one another, a first pair of hydraulic cylinders having one end pivotally mounted near the top of the frame on either side 35 of the truck body, a piston extending from the other end of each of the cylinders connected to each of the legs near the apex, said first pair of cylinders being substantially horizontal in the at rest position of the legs, vertical slotted guides at 40 the rear of the truck body on either side thereof, said free ends of the legs mounted in said guides,

a second pair of hydraulic cylinders vertically mounted at the rear of the truck body in cooperative relation with said guides, a piston extending from each of said second cylinders, a pivot connection between each of said free ends of the legs of the boom and the pistons slidably mounted in said guides, and means for controlling the operation of said hydraulic cylinders.

4. A portable folding boom for a vehicle having a supporting framework, said boom having a transport position in which it is approximately horizontal, and an operative position in which it is raised at different angles to the framework; said boom comprising a pair of upwardly converging legs joined together at one end in an apex, hydraulic cylinder means pivotally mounted on the framework and connected to said legs for moving the legs through an arc, substantially vertical guide means, said guide means including a pair of spaced vertical members providing parallel slideways, slide means shiftably mounted in each slideway for operative connection to the other ends of the legs whereby said legs are slidably supported for substantially vertical movement in said guide means, and power-driven extensible means operatively associated with said legs for vertically raising and lowering the legs in said guide means.

5. The apparatus according to claim 4, and in 30 which said extensible means is hydraulic cylinder means.
